US00D700112S

(12) **United States Design Patent**
Noble

(10) **Patent No.:** **US D700,112 S**
(45) **Date of Patent:** **** Feb. 25, 2014**

(54) **PROGRESSIVE RATE SPRING FOR A SUSPENSION**

(75) Inventor: **Shawn D. Noble**, Naperville, IL (US)

(73) Assignee: **Hendrickson USA, L.L.C.**, Itasca, IL (US)

(**) Term: **14 Years**

(21) Appl. No.: **29/426,559**

(22) Filed: **Jul. 6, 2012**

(51) LOC (10) Cl. **12-16**

(52) U.S. Cl.

USPC **D12/160**

(58) **Field of Classification Search**

(57) **CLAIM**

The ornamental design for a progressive rate spring for a suspension, as shown and described.

DESCRIPTION

FIG. 1 is a front elevation view of a progressive rate spring for a suspension having the inventive design;

FIG. 2 is a rear elevation view of the progressive rate spring for a suspension shown in FIG. 1, wherein the rear elevation view is identical to the front elevation view shown in FIG. 1; FIG. 3 is a left side elevation view of the progressive rate spring for a suspension shown in FIG. 1;

FIG. 4 is a right side elevation view of the progressive rate spring for a suspension shown in FIG. 1, wherein the right side elevation view is identical to the left side elevation view shown in FIG. 3;

FIG. 5 is a top plan view of the progressive rate spring for a suspension shown in FIG. 1;

FIG. 6 is a bottom plan view of the progressive rate spring for a suspension shown in FIG. 1;

FIG. 7 is a top right front corner perspective view of the progressive rate spring for a suspension shown in FIG. 1, wherein the top right front corner perspective view is identical to a top left rear corner perspective view of the progressive rate spring for a suspension;

FIG. 8 is a top left front corner perspective view of the progressive rate spring for a suspension shown in FIG. 1, wherein the top left front corner perspective view is identical to a top right rear corner perspective view of the progressive rate spring for a suspension;

FIG. 9 is a bottom right front corner perspective view of the progressive rate spring for a suspension shown in FIG. 1, wherein the bottom right front corner perspective view is identical to a bottom left rear corner perspective view of the progressive rate spring for a suspension; and,

FIG. 10 is a bottom left front corner perspective view of the progressive rate spring for a suspension shown in FIG. 1, wherein the bottom left front corner perspective view is identical to a bottom right rear corner perspective view of the progressive rate spring for a suspension.
